(57) **CLAIM**

The ornamental design for a packaging box, as shown and described.

DESCRIPTION

FIG. 1 is a perspective view of a packaging box of our new design, including a lid of the packaging box separated from a bottom of the packaging box.

FIG. 2 is a perspective view of the packaging box with the lid installed on the bottom;

FIG. 3 is a front elevation view of the packaging box of FIG. 1;

FIG. 4 is rear view thereof (the left and right sides being identical thereto);

FIG. 5 is a top view of the lid;

FIG. 6 is a bottom view of the lid;

FIG. 7 is a top view of the bottom;

FIG. 8 is a bottom view of the bottom;

FIG. 9 is perspective view of an interior of the lid; and,

FIG. 10 is perspective view of an interior of the bottom. In the drawings, the broken lines show portions of the packaging box that form no part of the claim.

1 Claim, 10 Drawing Sheets
